(57) **CLAIM**

We claim the ornamental design for an appliance interior with color, as shown and described.

DESCRIPTION

FIG. 1 is a perspective view of an appliance interior with color in a closed configuration according to a closed configuration of our design;

FIG. 2 is a front elevation view thereof;

FIG. 3 is a left side elevation view thereof;

FIG. 4 is a top plan view thereof;

FIG. 5 is a bottom plan view thereof;

FIG. 6 is a front elevation view of the appliance interior with color in an open configuration of our design;

FIG. 7 is an enlarged top left perspective view thereof;

FIG. 8 is an enlarged top right perspective view thereof;

FIG. 9 is a front elevation view thereof;

FIG. 10 is a partial left perspective view thereof;

FIG. 11 is a partial front elevation view thereof;

FIG. 12 is a partial left perspective view thereof in a first use condition of the open configuration;

FIG. 13 is a partial front elevation view of a right portion thereof;

FIG. 14 is a partial right perspective view thereof;

FIG. 15 is a partial front elevation view thereof;

FIG. 16 is a partial right perspective view thereof in a second use condition of the open configuration; and,

FIG. 17 is a partial front elevation view thereof.

The broken lines in the Figures are to show an environment and form no part of the claimed design.

The dark gray interior liner of the refrigerator compartment and refrigerator compartment doors are charcoal gray as shown in FIGS. 6-17. The charcoal gray has the following color characteristics according to the CIELAB system:

L 38.92

a-1.00

b-1.80
